BLADE SUPPORTING MEANS

Georges Monnet, New York, N. Y., assignor to
 Guardian Merchandising Corporation, West
 Montreal, Quebec, Canada, a corporation of
 Quebec, Canada

Application March 22, 1937, Serial No. 132,292

3 Claims. (Cl. 206—46)

This invention relates to methods of preserving razor blades and of depositing them upon safety razors and to means for carrying out these methods.

5 This patent application is a continuation in part of my co-pending patent applications, filed, respectively, April 1, 1936, Serial No. 72,068 and September 4, 1936, Serial No. 99,380.

Safety razor blades are now packed individually 10 in oiled paper and are enclosed in a paper envelope. Five, ten, or a larger number of such envelopes are packed together in packages made of heavier paper or of cardboard.

Past experience has shown that this method of 15 wrapping razor blades does not prevent the sharp edges thereof from rubbing against the paper wrapping, so that often the ends become dull before the user removes the razor blade from its wrapping for the first time.

20 At the present time, the removal of the razor blades from their wrappings and the placing of such razor blades upon safety razors is carried out by hand. The user must first open the paper envelope to produce the razor blade wrapped in oiled paper, then remove the oiled paper, and holding the razor blade in one hand, place it upon the safety razor, which is held in the other hand.

25 Everyday experience shows that the fingers or the hands of the user are frequently cut by the sharp edges of the razor blade when the blade is unwrapped and placed upon the safety razor. Furthermore, the form of the blade prevents the user from holding it securely, with the result that the blade is often dropped and damaged. It is 30 extremely inconvenient and dangerous to pick up a dropped blade when it lies upon a flat surface.

An object of the present invention is the provision of methods of removing a blade from its package and depositing it in its proper position upon a 35 safety razor without any contact with the hands or the fingers of the user, thereby eliminating the danger of injury to the user.

Another object is the provision of blade supporting means which will effectively protect the sharp 40 edges of the blades not only while the latter are not in use but also while they are being unwrapped and placed upon the safety razors.

The above and other objects of the present invention may be realized through the provision of 45 methods of transporting a blade which consist in securing a single blade by any suitable means upon a single supporting surface; the blade remains secured to this surface while it is being shipped, sold to a consumer, and kept by him prior to use.

50 55 When it is desired to use the blade, the supporting

surface is moved by the user to the required position adjacent the safety razor, and then the blade is freed from the safety razor, in any one of the following ways:

First, the supporting surface may be bent relatively to the blade, thereby freeing the blade and causing it to drop upon the safety razor.

Secondly, the supporting surface may be bent along with the blade until the means holding the blade upon the supporting surface frees the blade and causes it to drop upon the safety razor.

Thirdly, the blade may be moved or bent by any suitable means relatively to the supporting surface and thereby freed from engagement with said supporting surface.

Fourthly, the support, or a part thereof, may be moved sidewise relatively to the blade in the direction of the cutting edge thereof, thereby freeing the blade and placing it in the proper position upon the safety razor.

Fifthly, the blade may be drawn away from its support and deposited upon the razor by magnetic attraction, suction or the like.

Finally, the support and the blade may be separated from each other by a twisting or turning motion of one of these elements relatively to the other.

Several constructions may be used for carrying out these methods of separating the blade from its support, some of these constructions being shown by way of example only in the accompanying drawings, wherein

Figure 1 is a perspective view of a support carrying a blade;

Figure 2 is a section along the line 2—2 of 35 Figure 1;

Figure 3 is a perspective view of a blade support of a somewhat different type;

Figure 4 is a top view of the support shown in 40 Figure 3;

Figure 5 is a section along the line 5—5 of Figure 4;

Figure 6 is a perspective view of a third type of blade support illustrating the sidewise or sliding motion of the support relatively to the blade; 45

Figure 7 is a section along the line 7—7 of Figure 6.

Figures 8 and 9 are perspective views of a blade support which is somewhat similar to the one shown in Figure 6; Figure 8 showing the support 50 in its closed position, while Figure 9 shows the same support in its open position.

Figure 10 is a cross-section through the blade support shown in Figures 8 and 9;

Figure 11 shows another support wherein a 55

twisting or turning movement is used to free the blade from the support;

Figure 12 is a section along the line 12—12 of Figure 11;

5 Figure 13 illustrates diagrammatically the method of separating the blade from the support by a twisting movement;

Figure 14 is a top view of a different support and illustrates the method of freeing the blade 10 from its support by the bending of the blade;

Figure 15 is a section along the line 15—15 of Figure 14; and

15 Figure 16 is a perspective view of a support provided with overlapping flaps for holding the blade.

20 The safety razor blades used in connection with the present invention may be of any standard form, although in certain instances it is preferred to employ blades provided with two sharp cutting edges and two tongue portions formed by the dull edges of the blade and separated by shoulders from the cutting edges.

25 The blade supports manufactured in accordance with the present invention may be made of cardboard or of any other suitable fibrous and/or flexible material. In other instances, the supports should preferably be made of a hard, resilient material, such as metal, or metal alloy for example, steel or the like. The supports 30 should be wider than the blade, in order to protect its edges as well as the fingers of the user.

35 The surfaces of the blade support are preferably water-proofed and rust-proofed by waxing or by any other appropriate means.

35 The blade support 20 shown in Figures 1 and 2 is provided with flaps or bent-over portions 21 and 22, which have cut-out portions 23 and 24, respectively. The tongue ends 25 of a blade 26 pass through the openings 23 and 24 and fit 40 snugly into these openings, so that any shifting of the blade 26 upon the support 20 is prevented.

45 The middle portion of the support 20 is preferably provided with two parallel ridges 27 and 28, so that the blade 26 rests upon these ridges and not upon the flat surface of the support. The flap 21 is provided with similar parallel ridges 29, while the flap 22 is provided with parallel ridges 30. By this arrangement the blade 26 is 50 conveniently supported without contacting the entire surface of the support (Fig. 2).

55 The support 40 shown in Figures 3 and 4 comprises a middle portion provided with four projections or bulging portions 41, 42, 43 and 44. These projections are so located that when a blade 26 is placed upon the support, the two pairs of bulging portions will fit snugly between the two tongue ends 25 of the blade 26, thereby 60 maintaining the blade 26 in its position upon the support 40 and preventing any shifting thereof.

60 The support 40 comprises two flaps 45 and 46. The flap 45 is provided with two recessed portions 47 and 48 fitting over the projections 41 and 42, respectively. The flap 46 is provided with similar recessed portions 49 and 50 fitting over the projections 43 and 44, respectively. The flaps may be provided with ridges if desired.

65 In both constructions, the blades carried by the supports are freed by bending or moving the supports relatively to the blades.

70 When using the support 20 (Figs. 1 and 2), the user should keep one flap, for example, the flap 21, closed, and open the flap 22, thereby freeing one end of the razor blade. This freed end of the 75 razor blade is first placed upon the safety razor

and then the support 20 is removed, leaving the blade in its proper position.

The same support can be used for picking the blade off the razor after use, whereupon the blade carried by the support may be discarded, or it 5 may be preserved for subsequent use.

The support 40 (Figs. 3, 4, and 5) is used in a substantially similar manner, namely, the blade 26 is placed upon the razor by first opening one of the flaps 45 and 46, placing the freed end of 10 the blade upon the safety razor, and then removing the support.

Figures 6 and 7 illustrate a support which frees the blade carried thereby by relative sidewise sliding movements of the support. 15

The blade 26 is situated between two sheets or leaves 60 and 61. The two leaves 60 and 61 may be made of one piece and connected with each other by the edge portion 62.

20 As shown more clearly in Figure 7, only a portion of the blade 26 is enclosed between the sheets 60 and 61, the remaining portion of the blade projecting beyond these members. This projecting portion is enclosed between two leaves or sheets 63 and 64, which are interconnected by 25 the edge portion 65 and which overlap the leaves 60 and 61.

25 The lower supporting sheet 63 is provided with two projections 74, only one of which is shown in the drawings, and which are used to hold the 30 left-hand tongue portion 25 of the blade 26 (looking in the direction of Fig. 7). The supporting sheet 60 is provided with a similar pair of projections 66 used for holding the right-hand tongue portion 25 of the blade 26. 35

35 The upper leaf 61 is also provided with two recessed portions 67 into which fit the projections 66 provided upon the leaf 60. Two recessed portions 69 are formed on the leaf 64 opposite the 40 projections 74.

40 Two pairs of projections 68 and 70 constituting parts of the leaves 63 and 64 fit into recessed portions 72 and 73 formed in the leaves 60 and 61, respectively.

45 The sheets 60, 61, 63, and 64 may be provided with a central opening 71 which is somewhat larger than the central opening of the blade 26.

50 A support of this type may be provided with suitable ridges supporting and/or engaging the razor blade.

55 In this case, the blade 26 is removed from its support, first by pulling the leaves 63 and 64 away from the leaves 60 and 61 in the direction of the axis 7—7. Due to this pulling movement, the projections 70 and 68 will snap out of the 60 recessed portions 73 and 72, respectively, thereby freeing the leaves 63 and 64. After the removal of the overlapping portion 63, 64 of the support, a portion of the blade will be freed, so that it can be placed in its proper position upon the 65 safety razor. Then the inner leaves 60, and 61 are removed by a sidewise sliding motion, thereby freeing the blade entirely.

65 Another example of the freeing of the blade from the support by the sidewise sliding movement of one part of the support relatively to the other is illustrated in Figures 8, 9 and 10 of the drawings. The support shown in these figures 70 comprises a tray 80 having upturned flanges 81 and four projections 82 which are situated between the tongue ends 25 of a razor blade 26 and thereby hold the razor blade in position upon the tray 80, preventing any sidewise movement or longitudinal movements of the blade relatively to the tray. 75

The tray is enclosed by a cover 83 having flanges 84 which engage the flanges 81 and are slidable thereon. The cover 83 is also provided with a downwardly extending flange 85 which, in the closed position of the support, engages the edges of the flanges 81 thereby preventing any further movement of the cover 83 in the same direction. The cover 83 may also be provided with ridges 86 used for holding the blade in position.

10 In this case, the support while closed is turned over the guard of the razor blade, and then the cover 83 (and/or the tray 80) is removed by a sliding lengthwise movement, thereby causing the blade 26 to fall out of the tray 80 and to be deposited on the safety razor.

15 Figures 11, 12 and 13 illustrate the freeing of a blade by a turning or twisting movement. The support shown in these figures comprises a flat, substantially rectangular piece 90 provided with 20 a comparatively large central opening 91 and having two hooks 92 and 93 which are situated on opposite sides of each other and which are adapted to engage the dull tongue end portions 25 of a blade 26. As shown in Figure 13, the blade is 25 first placed with its support upon the safety razor and then the support is turned relatively to the blade in the direction of the arrow 94, whereby the hooks 92 and 93 will slide over the tongue portions 25 of the blade 26 and will free the blade, 30 so that it will be safely deposited upon the razor.

20 The construction shown in Figures 14 and 15 illustrates the method of freeing the blade from the support by bending the blade relatively to its support. The blade 26 is carried by a support 100 35 and is held thereon by any suitable projections 101. The support 100 is provided with a central opening 102 which extends to one of the side edges 103 of the support.

30 In addition to the projections 101, the blade 26 40 is preferably held upon the support 100 by any suitable spots of adhesive 104.

35 In order to free the blade, the support 100 is first placed adjacent the razor, then the blade is held firmly either manually or by any suitable 45 mechanical means, not shown in the drawings, while the support is moved in the direction of the cutting edge of the blade. During this movement the edges of the blade will gradually slide over the projections 101, thereby bending, pushing or 50 forcing the blade away from the support 100 until the bending force is sufficient to overcome the force of the adhesive 104 and liberate the blade entirely, which will then drop into its proper position upon the support.

55 The support 110 shown in Figure 16 comprises four projections 111 holding the blade 26, as well as overlapping portions 112 extending over the tongue ends 25 of the blade 26. In order to drop the blade 26 upon the safety razor, the user must 60 hold the support upside down over the razor and then bend the edges 113 and 114 of the support toward each other, thereby raising the portions 112 which will then free the blade, so that the latter will drop upon the safety razor.

65 When the user has finished shaving himself

with the blade, the support 110 may be placed over the blade which is lying upon the razor, thereby protecting the edges of the blade and preventing the user from cutting himself with the sharp edges of the blade. Or, the support 110 5 may be used for removing the blade from the safety razor, by means of the portions 112.

It is apparent that the specific illustrations shown above have been given by way of illustration and not by way of limitation and that 10 the structures above described are subject to wide variation and modification without departing from the scope or intent of the invention, all of which variations and modifications are to be included within the scope of the present invention. 15

What is claimed is:

1. Blade supporting means, comprising a single separate supporting means for each separate razor blade, said razor blade having at least one cutting edge and two dull edges having the form 20 of two tongue-shaped portions, said separate supporting means being somewhat wider than a razor blade and comprising at least one surface which carries said single razor blade and two overlapping hook-shaped portions adapted to engage different 25 sides of said tongue-shaped portions to hold said blade in position upon said surface and to prevent the shifting of said blade relatively to said surface, said overlapping hook-shaped portions freeing said blade when the supporting surface 30 is turned relatively to said blade around an axis which is substantially perpendicular to said surface.

2. Blade supporting means, comprising a single supporting means for a single razor blade having 35 inner edges adapted to engage projecting portions of a safety razor, said supporting means comprising a supporting surface carrying the blade and having an opening formed therein, said projecting portions of the safety razor being 40 adapted to extend through said opening, and means holding said blade and being located upon said surface in spaced relationship to said opening to permit the releasing of the holding means by a turning movement of said supporting surface 45 relatively to said razor blade upon the engagement of said inner edges of the razor blade with said projecting portions of the safety razor.

3. Blade supporting means, comprising a single supporting means for a single razor blade having 50 inner edges adapted to engage projecting portions of a safety razor, said supporting means comprising a supporting surface carrying the blade and having an opening formed therein, said projecting portions of the safety razor being adapted 55 to extend through said opening, and means engaging opposing corner sections of said blade to hold it in position upon said surface, said means being located upon said surface in spaced relationship to said opening to permit the releasing of 60 said razor blade when the supporting surface is turned relatively to said blade around an axis which is substantially perpendicular to said surface.

GEORGES MONNET, 65
